UNITED STATES PATENT OFFICE.

WALTER G. BURNS, OF FORT WAYNE, INDIANA.

GEAR CASING.

Application filed May 22, 1920. Serial No. 383,413.

To all whom it may concern:

Be it known that I, WALTER G. BURNS, a citizen of the United States of America, and resident of Fort Wayne, in the county of Allen and State of Indiana, have invented certain new and useful Improvements in Gear Casings, of which the following is a specification.

This invention relates to improvements in gear casing similar to the construction previously disclosed in my application, Sr. No. 326,593, for driving mechanism for ore concentrators, filed September 26, 1919, and the object of the invention is to provide a casing for supporting and containing mechanism and which is so constructed that oil placed in the casing for the lubrication of the contained mechanism will be prevented from seeping out from between the parts of the casing. A further object is to provide means for flooding mechanism with lubricating oil and sheltering the contained mechanism and oil from contamination with foreign matter.

The objects of the invention are accomplished by the construction illustrated in the accompanying drawings in which:

Fig. 1 is an end elevation of a driving mechanism for ore concentrators in which the present gear casing is included, a portion thereof being broken away and in section;

Fig. 2 is a rear elevation of Fig. 1 with parts broken away and in section;

Fig. 3 is a top plan view of one-half of the base of the casing, and

Fig. 4 is a bottom plan view of the corresponding half of the cover which forms part of the casing.

Similar characters of reference indicate corresponding parts throughout the several views and referring now to the same:

1 is the base, the ends 2 of which are counterparts oppositely arranged, and each is cast integral with a trough 3 which is transversely disposed. At each end of the trough is a chambered saddle 4 with a duct 5 extending from the bottom of its chamber 6 into the trough. In the upper edges of the trough, extending along the front, back and ends thereof, and across the adjacent parts of the saddles into the chambers 6 thereof, are corresponding continuous grooves 7, the external lips 8 along the grooves projecting higher than the internal lips 9 so that any excess of oil that may be splashed from the trough into the grooves

will overflow directly back into the trough or pass indirectly back thereinto through the chambers 6 and ducts 5.

A cover 10 is positioned over the trough and has at each end thereof a chambered cap 11 that rests upon the corresponding saddle 4 on the base, and has also at its front, back and ends continuous beads 12 that depend respectively into the adjacent grooves 7, in the trough, the arrangement of which serves as an oil trap that tends to prevent escape of the contained oil out from between the cover and trough. Overhanging ledges 13 along the lower edges of the cover extend over the corresponding external lips 8 on the trough, there being grooves 14 up into which the lips 8 project. The grooves 14 also extend across the adjacent faces of the caps 11 into the chambers 15 therein respectively. The ledges 13 prevent entrance of foreign matter from the exterior, into the grooves in the trough, and the grooves extending across the faces of the saddles and caps divert oil from between the faces into the chambers 15. The lips 8 and 9 on the trough and the grooves 7, and the ledges 13, beads 12 and grooves 14 of the cover are so proportioned and positioned that an open space 16 is left between each edge of the cover and corresponding edge of the trough when the caps rest in place respectively upon the saddles. Thus, creeping of oil by capillary attraction out from between the cover and trough is obviated. In the top of the cover 10 is a man-hole 17 which is closed by a lid 18, and in the front of the cover is made a hood 19 having an opening 20 through which an arm 21 extends from the exterior into the interior of the casing, the arm being actuated by the mechanism 22 contained in the casing. The hood has at its outer end an inwardly extending bead 23 for directing oil, that may splash against the inner walls of the hood, downwardly into the groove 7 in the front edge of the trough.

The mechanism 22 is supported with its shaft 24 extending through journal boxes 25 and 25' that are shaped to fit between the respective saddles 4 and corresponding caps 11, the boxes being clamped in place by tightening the bolts 26 that hold the caps and saddles together. The journal box 25 has near its outer end an internal annular recess 27 and a duct 28 leading therefrom for the passage of surplus oil from the journal box into the chamber 6 of the saddle,

and a ring 29 fitting tightly upon the shaft prevents oil from creeping out from the journal box along the shaft. The inner end of the journal box 25 has a slot 30 made 5 therein to permit a ring oiler 31 to bear upon the shaft 24.

In use, the trough is partially filled with a liquid lubricant, and as the contained mechanism 22 is actuated the lubricant is 10 churned by the moving parts which thereby become lubricated. Owing to the splashing about of the liquid in the casing, the grooves 7 in the edges of the trough become filled with the lubricant to the extent that 15 the lower edges of the beads 12 of the cover are submerged. Thus, the oil-charged atmosphere that is circulated by the moving mechanism is retained within the casing. Any overplus of oil that may enter the 20 grooves, either overflows the internal lips 9 back into the trough, or flows into the chamber 6 and returns into the trough through the ducts 5. In this manner the contained lubricant that is splashed about 25 within the casing instead of seeping out from between the trough and cover to the exterior of the casing, fills the traps between the edges of the trough and cover from which it overflows back into the trough.

30 What I claim is:—

1. In a casing for actuating apparatus, a base including a trough adapted to hold a body of lubricating oil, and having at its upper edges interior and exterior lips with 35 corresponding grooves intervening therebetween, the interior lips extending in a plane lower than the exterior lips; a cover supported over the trough and having pendent beads projecting respectively into the 40 grooves, there being open space between the lips and beads; and mechanism enclosed by the trough and cover adapted to agitate the oil and to be lubricated thereby; the said 45 grooves, lips and interposed beads forming a trap adapted to prevent escape of oil out from between the trough and cover.

2. In apparatus for inclosing mechanism to be actuated and lubricated therein, a trough having a chambered saddle at each end thereof for supporting the mechanism, 50 and a corresponding duct leading from each chamber into the trough, and having also grooves respectively in its upper edges that extend into the chambers; and a cover having a chambered cap at each end thereof adapted to rest upon the corresponding saddle and support the cover over the trough, and having also beads depending respectively from its lower edges into said grooves, there being open space between the 55 sides of the grooves and beads forming a trap.

3. In apparatus for enclosing mechanism to be actuated and lubricated therein, a trough having a chambered saddle at each 60 end thereof for supporting the mechanism, there being a duct leading from each chamber into the trough and having also a groove in each upper edge that extends across the upper faces of the saddles into the chambers; and a cover having a chambered cap at each end thereof adapted to fit upon the corresponding saddle and having along each of its lower edges a bead projecting into the corresponding groove in the trough and 65 an exterior ledge having a groove in its under side that extends across the adjacent lower faces of the caps into the chambers thereof.

4. In a gear casing a trough, and a cover 70 therefor, there being formed in the upper edge of the trough a groove with an overflow outlet into the trough, and on the cover a corresponding bead that is suspended in said groove, the adjacent surfaces of the 75 trough and cover being spaced apart.

In testimony whereof I affix my signature, in presence of two witnesses.

WALTER G. BURNS.
